UNITED STATES PATENT OFFICE.

EUGEN JULIUS DIETZMANN, OF LOS ANGELES, CALIFORNIA.

DESIGN FOR AN ELECTRIC-LIGHTING FIXTURE.

Application filed October 12, 1925. Serial No. 15,096. Term of patent 3½ years.

To all whom it may concern:

Be it known that I, EUGEN JULIUS DIETZMANN, a citizen of Germany (he having announced his intention of becoming a citizen of the United States), and a resident of Los Angeles, in the county of Los Angeles, and State of California, have invented a certain new, original, and ornamental Design for Electric-Lighting Fixtures, of which the following is a specification, reference being had to the accompanying drawings, forming part hereof.

The figure is a view showing in perspective an electric lighting fixture embodying my invention.

I claim:

The ornamental design for an electric lighting fixture, as shown.

In testimony whereof I have hereunto signed my name at Los Angeles, California, this first day of October, 1925.

EUGEN JULIUS DIETZMANN.
